(57) **CLAIM**

The ornamental design for a tilt-rotor, as shown and described.

DESCRIPTION

FIG. 1 is a front, perspective view of the tilt-rotor according to a first embodiment of the present design being used in a first mode;

FIG. 2 is a front view of the tilt-rotor of FIG. 1;

FIG. 3 is a left side view of the tilt-rotor of FIG. 1, the right side being a mirror image thereof;

FIG. 4 is a rear view of the tilt-rotor of FIG. 1; and

FIG. 5 is a top view of the tilt-rotor of FIG. 1.

FIG. 6 is a front, perspective view of the tilt-rotor according to the first embodiment of the present design being used in a second mode;

FIG. 7 shows a front view of the tilt-rotor of FIG. 6;

FIG. 8 shows a left side view of the tilt-rotor of FIG. 6, the right side being a mirror image thereof;

FIG. 9 shows a rear view of the tilt-rotor of FIG. 6; and

FIG. 10 shows a top view of the tilt-rotor of FIG. 6.

FIG. 11 is a front, perspective view of the tilt-rotor according to a second embodiment of the present design being used in first mode;

FIG. 12 shows a front view of the tilt-rotor of FIG. 11;

FIG. 13 shows a left side view of the tilt-rotor of FIG. 11, the right side being a mirror image thereof;

FIG. 14 shows a rear view of the tilt-rotor of FIG. 11; and

FIG. 15 shows a top view of the tilt-rotor of FIG. 11.

FIG. 16 is a front, perspective view of the tilt-rotor according to the second embodiment of the present design being used in a second mode;

FIG. 17 shows a front view of the tilt-rotor of FIG. 16;

FIG. 18 shows a left side view of the tilt-rotor of FIG. 16, the right side being a mirror image thereof;

FIG. 19 shows a rear view of the tilt-rotor of FIG. 16; and

FIG. 20 shows a top view of the tilt-rotor of FIG. 16.

The portions of the bottom of the tilt-rotor not shown in the drawings form no part of the claimed design.

The ornamental design for a tilt-rotor, as shown and described.

DESCRIPTION

FIG. 1 is a front, perspective view of the tilt-rotor according to a first embodiment of the present design being used in a first mode;

FIG. 2 is a front view of the tilt-rotor of FIG. 1;

FIG. 3 is a left side view of the tilt-rotor of FIG. 1, the right side being a mirror image thereof;

FIG. 4 is a rear view of the tilt-rotor of FIG. 1; and

FIG. 5 is a top view of the tilt-rotor of FIG. 1.

FIG. 6 is a front, perspective view of the tilt-rotor according to the first embodiment of the present design being used in a second mode;

FIG. 7 shows a front view of the tilt-rotor of FIG. 6;

FIG. 8 shows a left side view of the tilt-rotor of FIG. 6, the right side being a mirror image thereof;

FIG. 9 shows a rear view of the tilt-rotor of FIG. 6; and

FIG. 10 shows a top view of the tilt-rotor of FIG. 6.

FIG. 11 is a front, perspective view of the tilt-rotor according to a second embodiment of the present design being used in first mode;

FIG. 12 shows a front view of the tilt-rotor of FIG. 11;

FIG. 13 shows a left side view of the tilt-rotor of FIG. 11, the right side being a mirror image thereof;

FIG. 14 shows a rear view of the tilt-rotor of FIG. 11; and

FIG. 15 shows a top view of the tilt-rotor of FIG. 11.

FIG. 16 is a front, perspective view of the tilt-rotor according to the second embodiment of the present design being used in a second mode;

FIG. 17 shows a front view of the tilt-rotor of FIG. 16;

FIG. 18 shows a left side view of the tilt-rotor of FIG. 16, the right side being a mirror image thereof;

FIG. 19 shows a rear view of the tilt-rotor of FIG. 16; and,

FIG. 20 shows a top view of the tilt-rotor of FIG. 16.

The portions of the bottom of the tilt-rotor not shown in the drawings form no part of the claimed design.
